DESIGN FOR A COMBINED ROUGE BRUSH AND CASING THEREFOR

Irving Gold, New York, N. Y.

Application December 19, 1946, Serial No. 135,604

Term of patent 7 years

(Cl. D86—10)

To all whom it may concern:

Be it known that I, Irving Gold, a citizen of the United States, residing at the city, county, and State of New York, have invented a new, original, and ornamental Design for a Combined Rouge Brush and Casing Therefor, of which the following is a specification, reference being had to the accompanying drawing, forming part thereof.

Figure 1 is a side view of the combined rouge brush and casing therefor showing my new design.

Figure 2 is a side elevation viewed from either side of Figure 1.

Figure 3 is a view similar to Figure 1 showing the casing in partly open position.

Figure 4 is a view seen from one side of Figure 3 to show the position of the casing before completely open; and

Figure 5 is an elevation similar to Figure 3 showing the casing in fully open position with the brush exposed.

I claim:

The ornamental design for a combined rouge brush and casing therefor, as shown.

IRVING GOLD.
